UNITED STATES PATENT OFFICE

170,940

ILLUMINABLE CHRISTMAS ORNAMENT

John Petry, New York, N. Y., assignor to Raylite
Electric Corp., Bronx, N. Y., a corporation of
New York

Application October 4, 1952, Serial No. 21,698

Term of patent 7 years

(Cl. D29—23)

To all whom it may concern:

Be it known that I, John Petry, a citizen of the United States, and resident of New York, in the county of Queens, State of New York, have invented a new, original, and ornamental Design for an Illuminable Christmas Ornament, of which the following is a specification, reference being had to the accompanying drawings, forming a part thereof, and of which

Fig. 1 is a front perspective view of an illuminable Christmas ornament, showing my new design.

Fig. 2 is a rear perspective view thereof.

I claim:

The ornamental design for an illuminable Christmas ornament, as shown.

JOHN PETRY.
